UNITED STATES PATENT OFFICE.

GURDON W. HULL, OF WALLINGFORD, CONNECTICUT, ASSIGNOR TO SIMPSON NICKEL SILVER COMPANY, OF SAME PLACE.

DESIGN FOR HANDLES OF SPOONS, FORKS, &c.

Specification forming part of Design No. 7,759, dated September 15, 1874; application filed September 4, 1874.
[Term of Patent 7 years.]

To all whom it may concern:

Be it known that I, GURDON W. HULL, of Wallingford, in the county of New Haven and State of Connecticut, have invented a new Design for Spoon and Fork Handle; and I do hereby declare the following, when taken in connection with the accompanying drawings and the letters of reference marked thereon, to be a full, clear, and exact description of the same, and which said drawings constitute part of this specification, and represent a front view.

This invention relates to a design for handle for spoons, forks, and like articles of table service; and consists in the configuration and ornamentation of the handle, as shown in the accompanying illustration.

From the bowl or body the handle gradually contracts for about one-third its length, and then expands to the tip, the line of the edges being slightly curved. About midway of its length is a boss, *a*, projecting from each side. The tip of the handle is semi-quarterfoil in

shape. Below this boss *a* a simple branch runs down on the surface of the handle, and above the boss a "honeysuckle" branch extends up the surface of the handle to about the same distance as the branch below. A plain bead runs around the edge of the handle from the narrowest point upward, and at the tip runs into a central honeysuckle branch, all as shown in the accompanying illustration.

I claim—

The design for spoon and fork handle, consisting of the curved edges, terminating in the semi-quarterfoil at the tip, the central boss *a*, the surface, ornamented by a branch above and below the boss, and a bead around the edge, running into the honeysuckle branch at the tip, all as shown in the accompanying illustration.

G. W. HULL.
